UNITED STATES PATENT OFFICE.

GEORGE E. BROWN, OF LOWELL, MASSACHUSETTS.

CARRIER FOR BOTTLES.

1,209,807.

Specification of Letters Patent. Patented Dec. 26, 1916.

Application filed April 27, 1914. Serial No. 834,660.

To all whom it may concern:

Be it known that I, GEORGE E. BROWN, a citizen of the United States, residing at Lowell, county of Middlesex, State of Massachusetts, have invented an Improvement in Carriers for Bottles, of which the following description, in connection with the accompanying drawing, is a specification, like characters on the drawing representing like parts.

This invention has reference to carriers for bottles, jars and the like and has for an object to provide an improved carrier which may be cheaply manufactured and which 15 may be conveniently applied and removed from the neck of a bottle, jar or similar article.

The invention has also for an object, to provide a bottle carrier, having as a part 20 thereof, a piercing member which may be thrust through the paperboard cap of a milk bottle to remove said cap, the device being so designed that the carrier may provide a convenient support for the removed bottle 25 cap to support it in a sanitary manner, so that it may be re-placed when desired.

In accordance with my invention I provide a carrier constructed of wire, in which one piece of wire has a portion bent to form 30 a bail presenting substantially parallel side members and having another portion bent to provide a fixed jaw shaped to fit against the neck of a bottle and in which a second wire is bent to form a co-operating jaw and 35 is slidably connected at its ends to the parallel side members of the bail whereby the second wire forms a gravity operated jaw, the slide jaw being free to slide to closing or clamping position when the bail is 40 held in a proper position.

Referring to the drawing in which I have illustrated a preferred form of my invention, Figure 1 is a side view of my improved carrier illustrated as attached to the neck 45 of a milk bottle; Fig. 2 is a front view of the same; Fig. 3 is a perspective view of the carrier; Fig. 4 is a view of the carrier removed from the bottle illustrating its use to hold the removed bottle cap and Fig. 5 50 is a perspective view illustrating the manner of applying the carrier to a bottle.

Referring to the drawing in detail, I have illustrated a bottle carrier constructed in accordance with my invention consisting of 55 a wire 1, bent to form a bail, having substantially parallel side members, 2, 3, and

another portion bent to form a jaw 4 to fit against the side of the bottle. In the form illustrated the jaw 4 is formed by the ends of the wire which are connected together in any convenient manner. Preferably one end of the wire is sharpened and is bent to form a projecting piercing member more or less in the form of a hook as illustrated at 5. A second piece of wire 6, is bent to form a co-operating jaw to fit against the opposite side of the bottle neck. This jaw member 6 is connected to the bail 1 so as to move bodily longitudinally thereof and also so as to have a rocking movement. This is herein accomplished by providing the wire 6 with loops at its ends which loosely fit about the parallel side members of the bail, said loops having a loose enough fit to provide for the rocking movement as well as the movement longitudinally of the bail. The jaw 6, constitutes a gravity-actuated jaw which operates automatically to grip the bottle neck after the device has been applied to the bottle and when the bail is brought into vertical 65 position.

To apply the carrier to the bottle, the bail is turned into a more or less horizontal position this allowing the loose gravity actuated jaw 6, to move bodily on the bail and to rock or swing relative to the bail thereby to open away from the fixed jaw 4, and when the parts are in this position the device may be dropped over the neck of the bottle as shown in Fig. 5. To cause the device to grip 70 the bottle neck it is simply necessary to raise the bail 1 into the position shown in Figs. 1 and 2, for as the bail is raised the jaw 6 drops by gravity into its clamping position shown in Fig. 1 and as the weight of the 75 bottle comes on the bail, said jaw is automatically held in this position by virtue of the manner in which it is connected to the bail 1. To remove the device from the bottle the bail 1 is allowed to move over into the 80 position shown in Fig. 5, which position it will assume by gravity when it is released and when in this position it can be raised vertically from the bottle. When the parts are in the position shown in Fig. 5, the 85 bringing of the jaw 6 into clamping engagement with the bottle involves merely raising the bail 1 and this is the act which a person naturally performs in picking the bottle up.

My invention therefore, provides a device 90 which requires no special manipulation to cause it to grip the bottle neck or to be re-

leased therefrom and this result is secured because of the fact that the jaw 6 is loosely mounted on the bail and has a bodily movement thereon and also because of the fact 5 that it is a gravity actuated member which falls by gravity into position to engage the bottle neck as the bail is raised. Another advantage of my construction is that when the bail is released, it naturally assumes a 10 position as shown in Fig. 5, in which position it is below the top of the bottle and thus does not give any additional height thereto. Hence it is not necessary to remove the device from the bottle when the bottle is to 15 be placed in a refrigerator or on a shelf. Furthermore when the device is in its inoperative position shown in Fig. 5, it does not interfere at all with wiping off the neck of the bottle or pouring the contents from the 20 bottle.

The piercing member 5 provides a convenient means for removing the paper cap 10, that is commonly used for sealing a milk bottle and my device is so constructed that 25 it can be used to hold such paper cap when temporarily removed from the bottle. For instance if the device has been used to remove a paper cap then it may be laid on a table or other support in the position shown 30 in Fig. 4, in which position the paper cap is held out of contact with the table and will thus be kept sanitary. If desired, the device with the paper cap thereon may be applied to the bottle neck and retained thereon, in 35 which case the device would have the general position shown in Fig. 5.

I desire again to emphasize that in my device the jaw 6 is bodily movable freely on the bail and is a gravity actuated member 40 and that the operation of lifting the bottle involves merely raising the bail into its vertical position during which the jaw 6 falls by gravity into its operative position as shown in Fig. 1.

45 While I have illustrated a selected embodiment, of my invention, I do not wish to be limited to the constructional features shown.

Having fully described my invention, what I claim as new and desire to secure by Letters Patent is:

50

1. A carrier for bottles comprising a wire having one portion bent to form a bail and another portion bent to form a fixed jaw of permanent shape to fit against the neck of the bottle and a second wire bent to 55 form a gravity-actuated jaw which is slideable bodily on the bail, whereby when the carrier is applied to the neck of a bottle the gravity-actuated jaw will automatically come into operative position by the act of 60 bringing the bail into a vertical position.

2. A carrier for bottles comprising a bail presenting substantially parallel side members, a fixed jaw of permanent shape secured to the lower ends of said side members and a movable jaw slideable bodily on said parallel side members and loosely connected thereto so as to permit said jaw to rock as well as to slide whereby when the carrier is applied to the neck of a bottle the 65 bodily slideable jaw will automatically come into operative position by the act of bringing the bail into a vertical position.

3. In a carrier for bottles the combination 70 with a wire having one portion bent to form a bail presenting substantially parallel side members and another portion bent to provide a fixed jaw and having its end bent to provide a piercing member projecting laterally from said jaw; of a second wire bent to form 75 a co-operating jaw and having its ends loosely engaging and slidably mounted on said side members whereby the slideable jaw will be moved to operative position by gravity when the bail is brought into a vertical or inclined 80 position.

85 In testimony whereof I have signed my name to this specification, in the presence of two subscribing witnesses.

GEORGE E. BROWN.
